DRIVING CLAW

Alfred Lingg and Leo Goldhammer, Munich, Germany, assignors to Agfa Ansco Corporation, Binghamton, N. Y., a corporation of New York

Application December 14, 1934, Serial No. 757,539
In Germany December 14, 1933

5 Claims. (Cl. 88—18.4)

Our present invention relates to a driving claw device of the type in which the claw is driven through a crank and its motion controlled by a bearing slide.

5 Owing to its simplicity, this type of device is particularly suitable for advancing perforated photographic films. Known devices of this type, however, have not satisfied the stringent requirements of modern practice in reproducing sound 10 or pictures from films, regarding noiseless operation and a short feeding or driving movement.

It is an object of the present invention to provide a crank actuated claw which has properties hitherto possessed only by high-speed claws 15 which are moved over a complex path, for example, in respect to the short length of the feeding path.

It is a further object to provide a crank actuated gripper which runs with very little noise 20 and which is comparatively free from bearing or pivot wear, so that its life is prolonged.

A still further object is to provide a crank-actuated claw and its associated actuating mechanism which is more compact than the known 25 arrangements.

Further objects will be seen from the detailed specification following hereafter. Reference is made to the accompanying drawings in which

Fig. 1 shows a side elevation of a crank actuated driving claw according to this invention,

Fig. 2 shows a plan view of the device shown in Fig. 1,

Fig. 3 shows a side elevation of another crank actuated driving claw, and

Fig. 4 shows a plan view of the device shown in Fig. 3.

An advantage is obtained by the present invention in that the motion of a bearing slide which guides the claw-arm is provided by means 40 of an intermediate arm which is driven so that the claw enters into engagement with the member it is to drive in approximately a straight line and the driving stroke of the claw begins after the claw has completely engaged with the 45 driven member and ends before the claw has disengaged therefrom.

By employing an eccentric or the like to control the motion of the bearing slide the further advantage is obtained in that it is possible to 50 reduce the feed angle to 45° or even less. Such a short driving motion was hitherto only possible when the claw moved over complex curves or when one or more idle movements were provided between each driving movement of the 55 claw. The shaft driving such a claw must, there-

fore, move at a much higher speed than the crank shaft of a claw of the usual type. A high speed of rotation has, among other drawbacks the disadvantage that when used in sound film apparatus it causes undesirable noise.

In the arrangement described in detail below although the crank shaft has a low speed of rotation, its angular feed movement is small without it being necessary for the claw to be moved over say a figure 8 or other comparatively complicated curve. Moreover, in consequence of the omission of the previously necessary idle movements, the construction of the present device can be more compact than previously.

The invention will now be described with reference to the accompanying drawings.

Referring to Figs. 1 and 2, the claw arm 1, on the outer free end of which are fitted the claws 2, is pivotally mounted about a crank pin 3. A crank disc 4 is actuated by driving mechanism through a shaft 5. On the arm 1 near to the claws is arranged a bearing slide 6 which guides the arm 1. The slide 6 is controlled by an intermediate lever 7, which is pivotally connected with an oscillating lever 8 by a pin 9 and with the slide 6 by a pin 10. The intermediate lever 7 is pivoted about a bolt 11 fixed on the frame 12. The lever 7 is slotted at 13.

The oscillating lever 8 rocks about a pivot 14 which is likewise fixed on the frame 12. The oscillating lever 8 is provided with two parallel flanges 15 and 15a which engage the periphery of an eccentric 16 fixed on the crank shaft 5. Thus, when the shaft 5 is rotated the claw arm is moved on the one hand by the crank pin 3 and on the other hand by the eccentric 16, the oscillating lever 8, the intermediate lever 7 and the pivoting guide 6, in such a manner that the resultant path of a claw is the curve indicated by broken lines in Fig. 1. The other claw describes a similar curve.

In the construction shown in Figs. 3 and 4, the claw arm 26 is provided at one end with the claws 27 and at the other end is pivotally mounted on the crank pin 28. The crank 29 is mounted on the driving shaft 30. By means of the slide 31 the claws 27 are constrained to describe the curve 25 shown in Fig. 3. Fig. 3 shows the path of one claw as will be understood. The slide 31 is arranged to pivot about a pin 17 on a Z-shaped oscillating lever 18 which is pivotally carried on the shaft 30. The slide 31 is controlled by a connecting rod 19 pivotally carried on the crank pin 28 and which slides to and fro in a guide sleeve 20 mounted in a bore in

the spindle 24, so that it rocks a lever 21 fixed to the spindle 24. This movement of the lever 21 is transmitted to the oscillating lever 18 by a pin 22 which engages between two guide members 23, 23a, carried on the lever 18. The spindle 24 on which the lever 21 is mounted is carried in the wall 12 of the apparatus.

The curve 25 described by the teeth of the claw mechanism results from the following two partial movements: A reciprocating movement of the claw arm 26 is effected by means of the crank pin 28 mounted on the disk 29 which is rotated by the axle 30, and a reciprocating movement on an arc perpendicular to the first-named reciprocating movement is caused by the slide 31 which is moved by the Z-shaped lever 18. The lever 18 is rotatably mounted on the axle 30 and is moved by means of the lever 21 and the pin 22. The lever 21 is fixedly mounted on the spindle 24 and is reciprocated by means of the guide sleeve 20 in which slides the rod 19 driven by the crank pin 28 which simultaneously drives the claw arm 26.

What we claim is:

25. 1. A driving claw comprising in combination, a wall, a power driven shaft journaled in said wall, a crank disk mounted on said shaft, a pivot mounted on said crank disk, a claw arm mounted on said pivot, a slide mounted on said claw arm at a substantial distance from said pivot and the free end of said claw arm, an eccentric mounted on said crank disk, a first lever rotatably mounted on said wall, two flanges mounted on said first lever engaging the periphery of said eccentric, a second lever rotatably mounted on said wall with one end pivoted to the free end of said first lever and with its other end rotatably mounted on said slide, a slot provided in said second lever at a substantial distance between its two ends, and a pin fixedly mounted on said wall and engaging said slot.

2. A driving claw comprising in combination, a wall, a power driven shaft journaled in said wall, a crank disk mounted on said shaft, a pivot mounted on said crank disk, a claw arm mounted on said pivot, a slide mounted on said claw arm at a substantial distance from said pivot and the free end of said claw arm, a first lever rotatably mounted with its one end on said shaft and with its other end rotatably mounted on said slide, a spindle rotatably mounted on said wall, a guide sleeve mounted in the free end of said spindle, a rod rotatably mounted on said pivot and having one end engaging said guide sleeve, two guide members mounted on said first lever, a second lever fixedly mounted on said spindle, and a pin mounted on said second lever and engaging said guide members on said first lever.

3. A driving claw comprising in combination a wall, a power driven shaft journaled in said wall, a crank mounted on said shaft, a pivot mounted on said crank, a claw arm mounted on said pivot, a lever and means mounting the same for angular movement about a fixed axis, guide means carried by one end of said lever for slidably supporting said claw arm at a region between the claw end thereof and said pivot, and means actuated by said driven shaft including a sliding connection for oscillating said lever about said fixed axis for reciprocating said guide means on an arc segment perpendicularly to the reciprocating movement of said claw arm.

4. A driving claw as defined in claim 3 wherein said mounting means comprises a stub shaft spaced from and parallel to said driven shaft.

5. A driving claw as defined in claim 3 wherein said mounting means supports said lever for angular movement about the axis of said driven shaft.

ALFRED LINGG.
LEO GOLDHAMMER.
